UNITED STATES PATENT OFFICE.

ANSHELM BURTON ELMSTROM, OF MALDEN, MASSACHUSETTS.

SHOE STRETCHER.

Application filed November 15, 1920. Serial No. 424,007.

To all whom it may concern:

Be it known that I, ANSHELM BURTON ELMSTROM, a citizen of the United States, residing at Malden, in the county of Middlesex, State of Massachusetts, have invented a new and useful Shoe Stretcher, of which the following is a specification.

This invention relates to a shoe stretcher or tree. The principal objects of the invention are to provide a simple construction which can be adjusted and set in position very conveniently, and to provide simple and inexpensive means by which the two halves of the tree will be moved apart with a true parallel motion when the tree is set to stretch the shoe, and to provide improvements in the details of construction.

Reference is to be had to the accompanying drawings in which—

Fig. 1 is a side view of a preferred form of the invention, showing it in position in a shoe, which is represented in dotted lines;

Fig. 2 is a plan of a portion of the same, showing it expanded;

Fig. 3 is a similar view, showing it contracted;

Fig. 4 is a transverse sectional view on the line 4—4 of Fig. 2;

Fig. 5 is a side view of one of the arms of the toggle lever;

Fig. 6 is a similar view of a portion of the other arm, and

Fig. 7 is a detail elevation of the pivotal connecting and fastening means for these two arms.

The invention is shown as comprising a tree having a toe part consisting of two halves 10. These preferably are made of wood and provided with meeting surfaces which are in a plane. Each of these members is slotted out at 11 to form a horizontal slot or space extending in from the rear and terminating at a point back of the front or toe. These slots or spaces are horizontal and are located at about the center vertically. On account of the construction of the link shown herein the slot can be made very thin.

Inside of the device and within the slots are pivoted two links 12. These are pivoted on two vertical rods 13 extending through the shoe tree and are connected with a slide 14 by means of pivots 15. The same construction appears on both sides of the device. The slots 11 are recessed at the bottom to provide a space for the reception of

the slide 14 when the parts are closed as shown in Fig. 3. The pivots 13 and 15 are arranged at equal distances apart longitudinally so that the links 12 on each side are necessarily always parallel as shown. Therefore, when the slide 14 is moved in or out longitudinally, the motion of the links 12 is always parallel and also the relative motion of the two halves 10 is a parallel motion.

Pivottally connected with an upturned flange 20 on the rear end of the slide 14 by means of a pivot pin 21 is an arm 22. This, with a second arm 23, constitutes a toggle lever. This arm 22 is provided with a long slot 24 in which is located a projection of the same shape on a head 25. This head is provided with a bolt, on which operates a nut 26. This is knurled on the circumference and serves as a means for fastening the bolt to the arm 22.

The nut 26 has a cylindrical portion 27 which is adapted to engage in any one of a plurality of enlargements in a longitudinal slot 28 in the arm 23. These enlargements are of a circular character but are connected with each other by the overlapping of the circles as indicated in Fig. 5. In this way a longitudinal slot is provided which is continuous but which furnishes a positive pivotal connection with the arm 22 when the nut 26 is screwed up. The length of the enlarged shank 27 is greater than the thickness of the arm 23 so that when this nut is screwed up tight it does not restrict the free pivotal motion of the arms with respect to each other. However, when it is desired to change the adjustment it is not necessary to take the nut off, but merely to unscrew it enough so that the arm 23 can slide back and forth over the bolt beyond the end of the enlargement 27.

In addition to these features I have shown a wooden heel piece 29 fixed rigidly on the end of the arm 23, and an operating handle 30 on the end of the arm 22. The handle 30 preferably is formed by bending over the end of the sheet metal of which the arm 22 is composed. In the use of the device the pivot stud and nut 25—26 are adjusted to the proper position on the arm 23 and the nut screwed up. The parts are placed in the shoe in the manner indicated in Fig. 1. Then the handle 30 is pressed down until the toggle lever straightens out and preferably passes downwardly at the middle be-

yond the center. This holds it in that position until the handle 30 is raised.

By providing a longitudinal slot in each of the halves 10 for receiving all of the 5 operating parts located between the halves, I house these parts in such position that they are entirely out of sight when the device is collapsed. I also get a possibility of wide expansion without complicating the 10 device or making it expensive to manufacture or assemble. The adjustment is simple and very convenient and the operation of the device is easily acquired by those unfamiliar with this type of shoe stretcher.

15 Although I have illustrated and described only a single form of the invention I am aware of the fact that modifications can be made therein by any person skilled in the art without departing from the scope of the 20 invention as expressed in the claim. There-

fore, I do not wish to be limited to all of the details of construction herein shown and described, but what I claim is:—

In a shoe tree, the combination of a wooden sectional toe portion formed in 25 halves, a pair of parallel links pivoted to each half and adapted to extend therefrom toward the other half, the two corresponding links of each half making equal angles at all times with a central plane, a flat slide 30 pivots connected with said links on opposite edges of the slide and at equal distances apart, the two halves of said toe portion being provided with horizontal slots therein for reception of said links and slide, and 35 means for moving said slide longitudinally.

In testimony whereof I have hereunto affixed my signature.

ANSHELM BURTON ELMSTROM.
